UNITED STATES PATENT OFFICE.

WILLIAM W. HENRY, OF PHILADELPHIA, PENNSYLVANIA.

VENTILATOR FOR LOCOMOTIVE-CABS.

1,059,157.

Specification of Letters Patent.

Patented Apr. 15, 1913.

Application filed July 17, 1912. Serial No. 709,912.

To all whom it may concern:

Be it known that I, WILLIAM W. HENRY, a citizen of the United States, residing at Philadelphia, in the county of Philadelphia and State of Pennsylvania, have invented new and useful Improvements in Ventilators for Locomotive-Cabs, of which the following is a specification.

The primary object of this invention is the provision of a metallic ventilator specifically designed for the cabs of locomotive engines and which may be cheaply constructed and utilized in a great measure material which would otherwise go to waste. The invention in its broad aspect aims to devise a ventilator which may be advantageously applied to cars and vehicles generally and which is free from manually operable fastening means for securing the shutter in the required adjusted position, it being necessary only to operate the shutter controlling lever to move it to the required position where it will be secured automatically by novel holding means. The invention consists of the novel features, details of construction and combination of parts, which hereinafter will be more particularly set forth, illustrated in the accompanying drawings, and pointed out in the appended claims.

Referring to the drawings, forming a part of the specification, Figure 1 is a sectional view of the body portion of a locomotive engine provided with a ventilator embodying the invention. Fig. 2 is a longitudinal section of the ventilator on a larger scale on the line 2—2 of Fig. 3, looking in the direction of the arrows. Fig. 3 is a front view of the ventilator. Fig. 4 is a view similar to Fig. 2 of a modification. Fig. 5 is a section on the line 5—5 of Fig. 4, looking in the direction of the arrows. Fig. 6 is a detail section on the line 6—6 of Fig. 2, showing the parts on a larger scale. Fig. 7 is a detail perspective view of the operating lever.

Corresponding and like parts are referred to in the following description, and indicated in all the views of the drawings, by the same reference characters.

The numeral 1 designates the roof of a locomotive engine cab, car or vehicle to be equipped with a ventilator embodying the invention. An opening 2 is formed in the roof 1 for the egress of warm and vitiated air. A hood is arranged over the opening

2 and is secured to the roof 1 in any manner. The hood 3, shown in Figs. 1, 2 and 3, has its top inclined to the plane of the roof 1 in such a manner that one end of the top 60 rests upon the roof 1 and is secured thereto, as indicated at 4, whereas the opposite end is spaced from the roof 1, as indicated at 5. The hood 3 including the top and sides is formed of stout sheet metal and is secured to the roof 1 in any substantial way. A flange 6 is had at the upper edge of the top of the hood 3 and is preferably formed by bending an edge portion of the top downwardly. This flange 6 serves to strengthen and stiffen the top of the hood.

In the modification shown in Figs. 4 and 5 the only difference in the form of the ventilator is in the construction of the hood and in the provision of duplicate parts near the ends of the hood. In this construction the hood 3^a is open at opposite ends and the top parallels the roof 1. Each end of the top of the hood is reinforced by means of a pendent flange 6. Inasmuch as the devices near the ends of the hoods 3 and 3^a are substantially the same a detailed description of one only will be given and will suffice for a clear understanding of the operating means. A shutter 7 is located near each open end of the hood and its ends are flanged and apertured to receive bolts or like fastenings 8 by means of which the shutter is pivotally connected to the sides of the hood. The shutter 7 closes against flanges 9 and 10, whereby close joints are had. The flanges 9 and 10 consist of members or wings of angle bars which are secured to respectively the top of the hood and the roof of the cab, car or vehicle. The flange 9 is pendent from the top of the hood. The flange 10 issues from the roof 1 about in line with one end of the opening 2. The flanges 9 and 10 form stops against which the upper and lower edges of the shutter close. The flange 9 in addition to its function of providing a stop also serves to stiffen and strengthen the top of the hood. An arm 11 projects from the shutter 7 and receives a lateral stud 12 which is arranged to operate in a longitudinal slot 13 formed in a member 14 of the operating lever 15, which is pivoted at 16 to a bracket 17 pendent from the top of the hood 3. The operating lever 15 extends within convenient reach to be grasped when it is required to open or close the shutter 7. The shutter is

secured in the required position by fastening means comprising a bracket 18 which is secured to the top of the hood and is pendent therefrom, said bracket embodying two members 19 and 20 between which the member 14 of the operating lever is arranged to operate. A plurality of projections 21 extend from one of the members of the bracket 18 into the space formed between the two members 19 and 20. These projections 21 are made rounding to admit of the member 14 of the operating lever riding thereon when passing from one projection to the other. The projections 21 may be provided 15 in any manner and as shown consist of studs secured to the member 20. The member 14 of the operating lever has a longitudinal slot 22 into which any one of the projections 21 is adapted to extend, thereby 20 holding the operating lever and the shutter in the located position. The member 14 of the operating lever is held in engagement with the studs by means of the spring action of the members 19 and 20, said members moving outwardly when the member 14 is riding upon the projections 21 to clear 25 one of such projections and engage with another of the projections.

It is observed that all the essential parts 30 of the ventilator are constructed of sheet metal and the fixtures, such as the brackets 17 and 18 and the arm 11, may be formed of material which usually finds its way to the scrap pile, thereby utilizing such material with the result of economy of construction. It is further noted that the shutter may be held in the required position without the necessity of manipulating fastening means, such as thumb screws, pins or the 35 like, the securing means being automatic in action, both in releasing the operating lever upon the application thereto of sufficient force and in the securing of the operating lever in the adjusted position. In the form 40 of ventilator illustrated in Fig. 4 the shutter at one end of the hood is closed and the shutter at the opposite end may be opened and vice versa according to the direction of travel of the car.

From the foregoing description, taken in 50 connection with the accompanying drawings, the advantages of the construction and of the method of operation will be readily apparent to those skilled in the art to which the invention appertains, and 55 while I have described the principle of operation of the invention, together with the device which I now consider to be the best embodiment thereof, I desire to have it understood that the device shown is merely 60 illustrative, and that such changes may be made when desired as are within the scope of the claims appended hereto.

Having thus described the invention what is claimed as new, is:—

1. A ventilator comprising a hood having an edge portion of its top bent to form a reinforcing flange, a shutter pivoted between the sides of the hood, flanges at the top and the bottom of the hood for the shutter to close against, an operating lever for moving the shutter, a bracket secured to the hood and comprising spaced members between which the operating lever passes, and a plurality of projections extending from 75 one of the members of the bracket to engage the operating lever and hold it and the shutter in the adjusted position.

2. A ventilator comprising a hood, a shutter pivotally connected at its ends to the 80 sides of the hood, an operating lever comprising a member having a longitudinal slot, means having connection with the shutter and arranged to operate in the slotted portion of the operating lever, a bracket secured to the hood and comprising spaced spring members between which a slotted portion of the operating member passes, and a plurality of projections extending from 85 one of the members of the bracket to engage 90 the operating lever to hold it and the shutter in the located position.

In testimony whereof I affix my signature in presence of two witnesses.

WILLIAM W. HENRY.
